SWITCHING DEVICE.

1,413,639.

Specification of Letters Patent. Patented Apr. 25, 1922.

Application filed November 13, 1920. Serial No. 423,978.

To all whom it may concern:

Be it known that I, LEE R. WALLER, a citizen of the United States, residing at Westmount, in the Province of Quebec and Dominion of Canada, have invented certain new and useful Improvements in Switching Devices, of which the following is a full, clear, concise, and exact description.

This invention relates to electromagnetic switching devices and more particularly to switches of the step-by-step character such as those employed in telephone systems.

Switches of the type, in which an electromagnet is provided to advance the movable element from position to position in a step-by-step movement, are generally arranged to be controlled both directly and automatically. To control the switch directly an operating circuit, including a stepping magnet, is adapted to be successively opened and closed by means of a stepping relay. This relay is actuated by current impulses sent over an impulse circuit in accordance with some act performed by the person manipulating the apparatus. The stepping relay, in the well-known manner, by its intermittent action creates impulses in the operating circuit which cause the stepping magnet to advance the switch. To control the switch automatically the operating circuit, including the stepping magnet is arranged to be opened and closed automatically as by means of a set of interrupting contacts operated by the magnet itself. This method of controlling the movement of step-by-step switches especially useful where it is necessary to give the switch a hunting function and also for the purpose of restoring the switch to its normal position after it has been taken for use.

The source of current in these switch operating circuits is necessarily of comparatively high potential to insure a quick and certain action of the moving parts. The repeated breaking of the operating circuits tends to pit and wear away the interrupting contacts both on the stepping relay and the stepping magnets. To overcome this, condensers are provided, which receive the charge that would otherwise arc across the gap at the interrupting contacts.

The object of the present invention is the provision of a common means for protecting the interrupting contacts which produce impulses for operating a plurality of step-by-step switches and for protecting the contacts

of the stepping magnets of said switches while such switches are being operated automatically.

A feature of the invention relates to the provision of a single condenser for protecting the contacts of a stepping relay, which causes the operation of a plurality of step-by-step switches, and for protecting the contacts of the stepping magnets of the switches during the automatic operation of such switches.

The drawing, which forms a part of this application, shows a portion of an automatic telephone system utilizing a plurality of step-by-step electromagnetic switches to which the present invention is applied. The invention in its broadest scope is applicable to step-by-step switches of widely varying character, there being no limitation as to the construction, the number of movements or the manner of operating and controlling the same. In order to conveniently illustrate the invention, however, it is shown in connection with a plurality of ordinary single movement rotary step-by-step switches. Switches of this character are particularly useful in automatic telephone systems for registering purposes. Accordingly a few of the general elements of a register sender of the revertive impulse control type are shown.

A subscriber's line is illustrated terminating in the brushes of an individual line switch 102, 103, which have access to a circuit leading to a first or district selector switch, the brushes of which are illustrated at 111, 112. The line switch 102, 103 may be of any suitable character, preferably a step-by-step switch.

The district selector switch may be of the well-known power driven type, the circuits of which are controlled by a sequence switch 110. For a more detailed explanation of the individual line switch and the district selector switch illustrated herein, reference is made to the application by Stearn and Scudder, filed August 7, 1920, serial No. 402,041.

The register sender includes four step-by-step register switches 120, 125, 130 and 135 on which the digits of a desired designation may be registered. These switches are actuated by means of stepping magnets 124, 133, 151 and 157, respectively. For setting the register switches series of impulses are transmitted over the calling line to operate in succession the several stepping magnets. In

order to associate the impulse circuit in succession with the different stepping magnets and for controlling the sender circuits in other respects, a register controlling switch 5 140 is provided. Stepping magnet 109 is adapted to advance the brushes of the control switch 140 from position to position.

A detailed explanation will now be given showing the operation involved in setting 10 the several register switches by impulses transmitted over the calling line and in restoring the switches to their normal positions after their functions have been completed. Assume that the subscriber at sub- 15 station 100 wishes to extend a telephone connection. The removal of his receiver from the switchhook initiates the movement of the individual switch having brushes 102, 103, to extend his line to an idle district se- 20 lector in the way described in the above mentioned application by Stearn and Scud- 25 der, filed August 7, 1920, Serial No. 402,041. Following the seizure of the district switch, sequence switch 110 is advanced, as ex- 30 plained in the above mentioned application, to a position where its contacts 104 and 105, bottom, are closed. The closure of these contacts completes an impulse circuit including the calling subscriber's line and the 35 windings of the stepping relay 106, indi- vidual to the register sender. This circuit may be traced from battery through the right-hand winding of relay 106, lower contact 104, brush 102, through the loop of the calling substation, returning by way of brush 103, lower contact 105, left-hand winding of relay 106 to ground. Relay 106 completes a circuit from battery through the winding of slow-to-release relay 107 to 40 ground at the front contact and armature of relay 106. Relay 107 attracts its armature and closes a circuit for the energization of relay 108.

When the calling subscriber manipulates 45 his dial to transmit the first series of impulses, the first interruption of the line causes the release of the armature of stepping relay 106. Relay 107, being slow to release, maintains its energization and con- 50 sequently holds the circuit of relay 108 closed. The retraction of the armature of relay 106 causes the closure of the circuit from ground through the back contact of said armature, right-hand armature and 55 contact of relay 108, brush 114 of control switch 140, terminal 141, winding of stepping magnet 124 of the first switch 120, winding of slow-to-release relay 118 to bat- 60 tery and ground. Both the stepping magnet 124 and the slow-to-release relay 118 be- 65 come energized in this circuit. When, an instant later the line circuit is again closed at the end of the first impulse, relay 106 attracts its armature, the above traced circuit is opened, and the stepping magnet 124

deenergizes and advances brushes 119, 121 and 127 forward one position. Relay 118, however, being slow-to-release, maintains its armature attracted. Since the source of current in the operating circuit of magnet 124 70 is of comparatively high potential, the opening of this circuit at the back contact and armature of the stepping relay 106 tends to produce an arc which rapidly deteriorates these contacts. To overcome this effect a condenser 115 is connected to ground in a circuit in parallel to the circuit above traced 75 over the back contact and armature of the stepping relay 106. The circuit including condenser 115 may be traced from the operating source of current through the winding of relay 118, winding of magnet 124, terminal 141, brush 114, condenser 115, resistance 116 to ground. Hence, as the operating circuit is opened at the back contact and armature of relay 106, the energy 80 in the circuit is consumed or stored in the condenser 115 and does not produce an arc- 85 ing effect at the interrupting contacts.

For each of the following impulses of the series the stepping relay 106 is operated and the stepping magnet 124 advances the brushes of the first switch 120 through one position. At the termination of the series the stepping relay 106 remains energized 90 for a length of time sufficient to cause the deenergization of the slow-to-release relay 118. Relay 118 completes a circuit from battery through the winding and armature and contact of stepping magnet 109, contact 100 and armature of relay 118, brush 117, terminal 145, segment 126 of switch 120, brush 127 to ground. The stepping magnet 109 attracts its armature and interrupts its own circuit. On deenergizing this magnet ad- 105 vances the brushes 113, 114 and 117 to their second position terminals where the above traced energizing circuit of said magnet is opened at brush 117.

When the subscriber next manipulates the 110 dial 101 to transmit the second digit of the desired number, relay 106, on deenergizing, completes a circuit from ground through its armature and back contact, right-hand armature and contact of relay 115 108, brush 114, terminal 142, winding of the stepping magnet 133, winding of relay 118 to battery and ground. Magnet 133 and relay 118 become energized in this circuit. At the termination of the first impulse of the 120 series relay 106 attracts its armature and opens the above traced circuit, permitting the magnet 133 to deenergize and advance the brushes 128, 129 and 134 of the second register switch 125 to their first position 125 terminals. Relay 118, as above explained, remains energized. The sparking effect at the armature and back contact of relay 106 is prevented by the same condenser 115. This time said condenser is connected in a 130

circuit from battery through the winding of relay 118, winding of stepping magnet 133, terminal 142, brush 114, condenser 115, resistance 116 to ground. At the end of the 5 second series of impulses relay 106 maintains its armature operated to permit de-energization of the slow-to-release relay 118. Relay 118 now completes a circuit from battery through the winding and armature of 10 magnet 109, contact and armature of relay 118, brush 117, terminal 146, segment 136 of switch 125, brush 134 to ground. Magnet 109 attracts its armature, interrupts its own circuit and advances the brushes of the control switch 140 to their next position terminals. 15

On the first impulse of the third series transmitted over the calling line, relay 106 retracts its armature and completes a circuit 20 from ground through the back contact of said armature, right-hand armature and contact of relay 108, brush 114, terminal 143, winding of magnet 151, winding of relay 118 to battery and ground. At the end of the 25 first impulse relay 106 attracts its armature, opens the above traced circuit to cause the deenergization of the stepping magnet 151. Magnet 151, on releasing its armature, advances the brushes 137, 138 and 152 of 30 the third register switch 130. The condenser 115 is now included in a circuit from battery through the winding of relay 118, winding of stepping magnet 151, terminal 143, brush 114, condenser 115, resistance 116 to ground and consequently prevents 35 sparking at the interrupting contacts of relay 106. At the end of the series of impulses relay 118 becomes deenergized and completes a circuit from battery through 40 the winding and armature and contact of magnet 109, contact and armature of relay 118, brush 117, terminal 147, segment 153 of switch 130, brush 152 to ground. Magnet 109 is operated, interrupts its own circuit 45 and moves the brushes of the control switch onto their next set of terminals.

Responsive to the first impulse of the last series transmitted from the calling subscriber's station, relay 106 becomes deenergized 50 and releases its armature. A circuit is there- 55 upon closed from ground through the armature and back contact of said relay, right-hand armature and contact of relay 108, brush 114, terminal 144, winding of stepping magnet 157, winding of relay 118 to battery and ground. Magnet 157 and relay 118 becomes energized in this circuit. At the end of the first impulse relay 106 at- 60 tracts its armature and opens the above circuit to permit the deenergization of stepping magnet 157, which, in turn, advances the brushes 154, 155 and 158 of the register switch 135 forward one position. The circuit including condenser 115, which again 65 serves to eliminate the sparking effect at

the operating contacts of the stepping relay 106, may now be traced from battery through the winding of relay 118, winding of magnet 157, terminal 144, brush 114, condenser 115, resistance 116 to ground. After the last 70 impulse of the series has been sent relay 118 finally deenergizes and completes a circuit from battery through the winding and armature and contact of stepping magnet 109, contact and armature of relay 118, brush 117, terminal 148, segment 159 of switch 135, brush 158 to ground. Magnet 109 attracts its armature, interrupts its own circuit and advances the brushes 113, 114 and 117 to their next position terminals. 80

In the manner fully explained in the above mentioned application, filed August 7, 1920, Serial No. 402,041, the register sender controls the operation of the district selector and succeeding switches in accordance with the designation recorded to establish a talking connection between the calling line and the desired called line. Following the completion of the control of the selective switches the district sequence switch 110 is advanced to a position for completing the talking circuit. In this position the lower contacts 104 and 105 are opened to bring about the release of the register sender. The opening of these contacts severs the impulse circuit and relay 106 becomes deenergized. After an interval the slow-to-release relay 107 retracts its armature and opens the circuit of relay 108. Relay 108 immediately establishes a circuit from battery through the winding and armature and contact of magnet 109, contact and armature of relay 118, brush 117, terminal 160, contact and left-hand armature of relay 108 to ground. Magnet 109 interrupts its own circuit and advances the brushes of the control switch to the next position. In this position of the control switch a circuit is established from battery through the winding of relay 118, winding and armature and 100 contact of stepping magnet 124, segment 122, brush 121, terminal 161, brush 113 to ground at the contact and left-hand armature of relay 108. Stepping magnet 124 repeatedly interupts its own circuit and advances the brushes 119, 121 and 127 forward in a step-by-step movement. During this action the contacts of the stepping magnet 124 are protected by a circuit including the condenser 115 to prevent sparking. The 105 circuit of the condenser 115 may be traced from battery through the winding of relay 118, winding of magnet 124, terminal 162, brush 114, condenser 115, resistance 116 to ground. When the brushes of switch 120 have reached their normal position, brush 121 disengages segment 122 and the interrupting circuit of magnet 124 is opened. The switch therefore comes to rest and after an 110 interval relay 118 becomes deenergized. A 120 125 130

circuit is now closed from battery through the winding and armature and contact of magnet 109, contact and armature of relay 118, brush 117, terminal 166, terminal 123, brush 121, terminal 161, brush 113, contact and left-hand armature of relay 108 to ground. Magnet 109 advances the brushes of the control switch to their next set of terminals.

10 A circuit is now closed as follows for restoring the register switch 125 to its normal position: battery, through the winding of relay 118, winding of magnet 133, armature and contact of said magnet, segment 131, brush 129, terminal 163, brush 113, contact and left-hand armature of relay 108 to ground. The stepping magnet 133 automatically interrupts its own contacts and advances the brushes of switch 125 to their normal position. During the operation of switch 125 the contacts of the stepping magnet 133 are protected by condenser 115 which is included in the following circuit: battery, through the winding of relay 118, winding of magnet 133, terminal 164, brush 114, condenser 115, resistance 116 to ground. When the switch is fully restored brush 129 opens the circuit of the stepping magnet 133 and relay 118 later becomes deenergized. 30 Relay 118 completes a circuit from battery through the winding and armature and contact of magnet 109, contact and armature of relay 118, brush 117, terminal 165, terminal 132, brush 129, terminal 163, brush 113 to ground at the contact and left-hand armature of relay 108. Magnet 109 advances the control switch 140 to the next position.

In a similar manner the remaining two 40 registers 130 and 135 are automatically restored to their normal position by their respective stepping magnets 151 and 157. The contacts of these magnets are protected by the condenser 115, as explained. When the 45 last register switch 135 has been restored, the register control switch 140 moves to the position in which it is shown in the drawing and all apparatus is therefore restored to normal ready for subsequent use.

50 What is claimed is:

1. In combination, a plurality of switches each having a movable element, an operating magnet for each switch, a relay having interrupting contacts for sending impulses to said switches, said operating magnets being responsive to such impulses for actuating said movable elements, interrupting contacts for each of said operating magnets for causing the automatic movement of said 55 movable elements, and a common means for protecting the interrupting contacts of said relay and the contacts of all of said magnets.

2. In combination, a plurality of switches each having a movable element, an operating magnet for each switch, a relay having

a set of contacts, means for sending impulses to said relay, said relay responding to said impulses to open and close its contacts, means controlled by said contacts for sending impulses to each of said switches, said operating magnets being responsive to such impulses for actuating the movable elements, interrupting contacts for each of said magnets for causing the automatic movement of said movable elements, and a common means for protecting the contacts of said relay and the contacts of all of said magnets. 70

3. In combination, a plurality of switches each having a movable element, an operating magnet for each switch, a relay having interrupting contacts for sending impulses to said switches, said operating magnets being responsive to such impulses for advancing said movable elements to given positions, 80 interrupting contacts for each of said magnets for causing the automatic movement to normal of said movable elements, and a common means for protecting the contacts of said relay and the contacts of all of said magnets. 85

4. In combination, a plurality of switches each having a movable element, an operating magnet for each switch, an impulse circuit, a relay having interrupting contacts 95 for sending impulses over said circuit, means for associating said circuit with each of said magnets, said magnets being responsive to the impulses in said circuit for actuating said movable elements, interrupting contacts for each of said magnets for causing the automatic movement of said movable elements, and a common means for protecting the interrupting contacts of said relay and the contacts of all of said magnets. 100

5. In combination, a plurality of switches each having a movable element, an operating magnet for each switch, an impulse circuit, a relay having interrupting contacts for sending impulses over said circuit, means 110 for associating said impulse circuit in succession with said magnets, said magnets being responsive to the impulses in said circuit for actuating said movable elements, interrupting contacts for each of said magnets for causing the automatic movement of said movable elements, and a common means for protecting the interrupting contacts of said relay and the contacts of all of said magnets. 115

6. In combination, a plurality of switches each having a movable element, an operating magnet for each switch, an impulse circuit, a relay having interrupting contacts for sending impulses over said circuit, a switch 125 for associating said impulse circuit in succession with said magnets, said magnets being responsive to the impulses in said circuit for actuating said movable elements, interrupting contacts for each of said magnets. 130

nets for causing the automatic movement of said movable elements, and a common means for protecting the interrupting contacts of said relay and the contacts of all of said 5 magnets.

7. In combination, a plurality of switches each having a movable element, an operating magnet for each switch, a relay having interrupting contacts for sending impulses to 10 said switches, said operating magnets being responsive to such impulses for actuating said movable elements, a circuit for each of the operating magnets, a set of interrupting contacts for opening and closing each of said 15 circuits to cause the automatic movement of said movable elements, and a common means for protecting the interrupting contacts of said relay and the contacts of all of said magnets.

8. In combination, a plurality of switches each having a movable element, an operating magnet for each switch, an impulse circuit, a relay having interrupting contacts for sending impulses over said circuit, means 20 for associating said impulse circuit in succession with said operating magnets, said operating magnets being responsive to the impulses in said circuit for actuating said movable elements, a circuit for each of said 25 operating magnets, a set of interrupting contacts for each of said magnets for opening and closing said circuits to cause the automatic movement of said movable elements, and a common means for protecting the interrupting contacts of said relay and the contacts of all of said 30 magnets.

9. In combination, a plurality of step-by-step switches each having a movable element, a stepping magnet for each switch, a 35 relay having interrupting contacts for sending impulses to said switches, said stepping magnets being responsive to such impulses for actuating the movable elements, interrupting contacts for each of said stepping 40 magnets for causing the automatic movement of said movable elements, and a common means for protecting the interrupting contacts of said relay and the contacts of all of said 45 magnets.

10. In combination, a plurality of step-by-step switches each having a movable element, a stepping magnet for each switch, a relay having interrupting contacts for sending impulses to said switches, a step-by-step 50 auxiliary switch for associating in succession said relay with said step-by-step switches, said stepping magnets being responsive to such impulses for actuating the movable elements, interrupting contacts for 55 each of said stepping magnets for causing automatic movement of said movable ele-

ments, and a common means for protecting the interrupting contacts of said relay and the contacts of all of said magnets.

11. In combination, a plurality of step-by-step switches each having a movable element, a stepping magnet for each switch, a relay having interrupting contacts for sending impulses to said switches, said stepping magnets being responsive to such impulses 65 for actuating said movable elements, interrupting contacts for each of said stepping magnets for causing the automatic movement of the movable elements, and a single device for protecting the interrupting contacts of said relay and the contacts of each 70 of said magnets.

12. In combination, a plurality of switches each having a movable element, an operating magnet for each switch, a relay having 75 interrupting contacts for sending impulses to said switches, said operating magnets being responsive to such impulses for actuating said movable elements, interrupting contacts for each of said operating magnets for causing the automatic movement of said 80 movable elements, and a single condenser for protecting the interrupting contacts of said relay and the contacts of all of said magnets.

13. In combination, a plurality of switches each having a movable element, an operating magnet for each switch, a relay having interrupting contacts for sending impulses to said switches, said operating magnets being responsive to such impulses for actuating said movable elements, interrupting contacts for each of said operating magnets for causing the automatic movement of said 85 movable elements, a condenser, and means for associating said condenser with the interrupting contacts of said relay and with the contacts of all of said magnets.

14. In combination, a plurality of switches each having a movable element, an operating magnet for each switch, a relay having interrupting contacts for sending impulses to said switches, said operating magnets being responsive to such impulses for actuating said movable elements, interrupting contacts for each of said operating magnets for causing the automatic movement of said 95 movable elements, a condenser, and a switch for associating said condenser in succession with the interrupting contacts of said relay 100 and with the contacts of said operating magnets.

In witness whereof, I hereunto subscribe my name this 9th day of November, A. D. 1920.

LEE R. WALLER.
